(74) Attorney, Agent, or Firm — Gardner, Linn, Burkhardt
& Ondersma LLP(57) **CLAIM**

The ornamental design for a vehicle diagnostic device, as shown and described.

DESCRIPTION

FIG. 1 is a front perspective view of the vehicle diagnostic device;

FIG. 2 is a front plan view of the vehicle diagnostic device of FIG. 1;

FIG. 3 is a front side edge elevation view of the vehicle diagnostic device of FIG. 1;

FIG. 4 is a right side edge elevation view of the vehicle diagnostic device of FIG. 1;

FIG. 5 is a rear side edge elevation view of the vehicle diagnostic device of FIG. 1;

FIG. 6 is a left side edge elevation view of the vehicle diagnostic device of FIG. 1; and,

FIG. 7 is a bottom plan view of the vehicle diagnostic device of FIG. 1.

The broken lines in the drawings are for the purpose of illustrating portions of the vehicle diagnostic device that form no part of the claimed design.

1 Claim, 7 Drawing Sheets(56)
